UNITED STATES PATENT OFFICE

JOHN A. LAMONT AND FREDERICK A. LORENZ, JR., OF CHICAGO, ILLINOIS, ASSIGNEES
TO AMERICAN STEEL FOUNDRIES, OF CHICAGO, ILLINOIS, A CORPORATION OF NEW
JERSEY

CAST STEEL BOTTOM DROP DOOR

Application filed April 24, 1929. Serial No. 357,630.

This invention pertains to drop doors, and more particularly to cast steel drop doors for railway cars and the like.

An object of the invention is to provide a reinforced cast steel drop door for railway cars and the like which presents a substantially uninterrupted load carrying surface to the load.

Another object of the invention is to provide a cast steel drop door wherein the hinge butts are secured thereto in such a manner as to place the fastening means in multiple shear.

Still another object of the invention is to provide a reinforced cast steel drop door wherein the hinge butts are disposed in substantial alignment with certain of the reinforcements and wherein the fastening means of the hinge butts are disposed in multiple shear.

A further object of the invention is to provide a drop door having members formed thereon for reinforcing the door and for providing cooperating means for the operating mechanism.

Still further object is to provide a drop door having a portion of the load carrying plane formed to provide stiffening means for the door and also to provide cooperating structure for the operating mechanism without affecting discharge of the load when the door is in open position.

With these and various other objects in view, the invention may consist of certain novel features of construction and operation, as will be more fully described and particularly pointed out in the specification, drawings and claims appended hereto.

In the drawings, which illustrate an embodiment of the device and wherein like reference characters are used to designate like parts—

Figure 1 is a fragmentary top plan view of one form of cast steel door embodying the invention;

Figure 2 is an enlarged fragmentary top plan view of a portion of the door illustrated in Figure 1, showing one method of fastening the hinge thereto;

Figure 3 is a fragmentary end elevation of the hinge and door construction illustrated in Figure 2;

Figure 4 is a fragmentary sectional side elevation of the door and hinge construction illustrated in Figure 2, the same being taken substantially in the plane as indicated by the line 4—4 of Figure 2;

Figure 5 is a fragmentary top plan view of another form of cast steel drop door embodying the invention;

Figure 6 is an enlarged fragmentary top plan view of a portion of the door illustrated in Figure 5, showing one method of fastening the hinge thereto;

Figure 7 is a fragmentary end elevation of the hinge and door construction illustrated in Figure 6;

Figure 8 is a fragmentary sectional side elevation of the door and hinge construction illustrated in Figure 6, the same being taken substantially in the plane as indicated by the line 8—8 of Figure 6;

Figure 9 is a top plan view of still another form of drop bottom door embodying the invention;

Figure 10 is a transverse sectional elevation of the modified form of drop door, the same being taken substantially in the plane as indicated by the line 10—10 of Figure 9;

Figure 11 is a side elevation of the modified form of drop door illustrated in Figure 9;

Figure 12 is an end elevation of the modified form of drop door illustrated in Figure 9, the same being taken at the hinge edge thereof;

Figure 13 is a top plan view of yet another modified form of drop door embodying the invention;

Figure 14 is a side elevation of the modified form of drop door illustrated in Figure 13, showing the relation of said door to the adjacent car structure; and

Figure 15 is a transverse sectional elevation of the modified form of drop door, the same being taken substantially in the plane as indicated by the line 15—15 of Figure 13.

Referring first of all more particularly to the form of drop door illustrated in Figure 100

1, the door is preferably of cast construction and includes an upper plate 20 presenting a smooth upper surface to the load to be carried, said plate being provided with 5 side marginal flanges 22, a front end marginal flange 24 continuous and integral with the marginal flange 22, and a rear marginal flange 26 preferably integral with and formed as a continuation of the side marginal 10 flanges 22. The marginal flanges 22 and the under side of the door plate 20 are provided with transverse integral reinforcing ribs 28, in effect forming panels on the door plate and sectionalizing the longitudinally extending 15 marginal flanges 22. The depending marginal flanges and the transverse flanges 28 are provided with projecting or reentrant flanges 30 for the purpose of providing a reinforcement for the door plate of greater 20 stiffness and strength. The transverse ribs may be formed with lightening holes 32 which are also provided for shrinkage purposes, all consistent with good foundry practice.

25 The rear flange 26 is interrupted as at 34 in a plurality of places for the purpose of providing attachments for the hinge butts, any number of which may be used, and the flanges at the interrupted portions are 30 formed with continuations 36 extending inwardly to a point adjacent the boss 38 formed on the upper side of the door sheet, and are provided with a lower wall 40 forming a pocket for the reception of the hinge butts 35 42. The hinge butts are substantially H-shaped in transverse section and are formed with a plurality of bosses 44 provided with suitable apertures registering with apertures formed in the boss 38 for the reception of 40 rivets 46 extending therethrough and through the lower wall 40 for fastening the hinge butts in place. The rivets 46 are preferably provided with a countersunk head and may be provided with a snap point.

45 The bosses 44 are joined together by webs 48 and side vertical walls 50, and are provided with a depending portion 52 disposed substantially in the plane of the rear door flange and apertured to receive the pin 54 50 for securing the hinge butt to the hinge pedestal or bracket 56. The hinge bracket 56 is provided with an arcuate portion 58 adapted to receive and support a corresponding arcuate surface of the member 52 55 for supporting the same and forming a bearing therefor so that the pin 54 takes no stress but merely serves to secure the door against displacement. The hinge butt may be provided with an upstanding ledge 60 60 and a rear wall 62 for forming a continuation of the door plate and the marginal flange 26.

With this construction it will be seen that the rivets 46 are placed in double shear and 65 are not stressed when the door is in closed

position and when the door is in closed position no bending stresses are carried on the pin 54.

In the modification illustrated in Figures 5 to 8 inclusive, the door plate 70 is provided with front and rear depending marginal flanges 72 and 74 and depending side marginal flanges 76 which preferably slope outwardly for a snug fit with corresponding cross members of the car. Longitudinal reinforcing members 78 are formed on the under side of the door structure and are disposed between the front and rear flanges 72 and 74 and are integral therewith, said depending members being formed so that they may form cooperating members with the lifter mechanism for the door. The members 78 are spaced apart as at 80 and are formed with a bottom wall 82 forming a recess for receiving the hinge butt 84. Said hinge butt extends into a pocket and is secured to the portions 80 by means of transverse rivets 86 so that no fastening means are presented to the load, the hinge butt being preferably disposed in an interrupted portion 88 of the rear flange 74 and provided with a rear wall 90 and a ledge 92 forming a continuation of the rear flange 74 and the door plate. The hinge 84 is provided with a head 94 disposed substantially in the plane of the rear flange and provided with an aperture for receiving the pin 96 securing the hinge butt to the hinge bracket 56 which has already been described.

In the modification illustrated in Figures 9 to 12 inclusive, the door plate 100 is provided with front marginal flange 102 preferably formed with a reentrant portion 104, said flange being integral with side marginal flanges 106, which marginal flanges are integral with the rear marginal flange 108. In this modification, the rear flanges are interrupted as at 110 for the reception of hinge butts 112, for cooperative engagement with a suitable hinge bracket as has been described, the rear flange being preferably reentrant as at 114 and formed deeper adjacent the longitudinal center line of the door than at the side marginal flanges. The side marginal flanges preferably slope outwardly to cooperate with and fit snugly against adjacent car structure.

The door plate 100 is formed with longitudinally depressed panel portions 116 preferably in alignment with the hinge butts and extending forwardly to a point adjacent the front flange 102, said panels being formed with marginal flanges 118 forming tracks for door operating mechanism, and the inner walls 120 of said panel portions may be reinforced by transverse ribs 122 formed integral with said panels and with the door plate. The panels merge into the door plate adjacent the forward flange 102 by means of a sloping wall portion 124 so

formed that when the door is in dump position, the load will slide freely over the door plate and be discharged without pocketing any of said load. The lower wall 126, which is a continuation of the wall 124, is formed to provide members 128, 130 and 132 forming a pocket for receiving a portion of the hinge butt 112, which is substantially the same as hinge butt 52, being provided with a plurality of bosses 134 and secured to the door plate by means of the rivets 136.

In the modification illustrated in Figures 13 to 15 inclusive, the door plate 150 is formed to present a flat upper surface to the load, and said door plate is provided with front and rear marginal flanges 152 and 154 formed integral with depending sloping side marginal flanges 156 which cooperate with cross members 158 of a car, as shown in Figure 15. The door in raised position, if in a car of the flat bottom type, may abut against the under edge of the side sill 160 and the under edge of a plate 162 spaced from said side sill and defining the load discharging opening. The door is provided with longitudinally extending integral depending members 164 formed on the flat under side with a track portion 166 for cooperative relation with the door operating mechanism, the track being provided with a sloping portion 168 merging into the front flange 152. The track members merge at the end thereof with an integral hinge butt 170 formed integral therewith and with the depending end flange 154, the hinge butt being provided with an opening 172 adapted to have pivotal relation with a bracket, which may be similar to the bracket 56 and secured to the car structure. The door is formed between the front and rear marginal flanges and the depending ribs 164 with integral intersecting cross ribs 174 said ribs being formed to merge into the ribs 164 adjacent the door plate 150 and to increase in height to the longitudinal center line of the door, as shown in Figure 15, the ribs being formed with bosses 176 at the intersections. The intersecting ribs merge into the front and rear flanges preferably through a single short rib 178 and merge into the ribs 164 preferably by a short rib 180.

With this construction, a very compact and strong reinforced plate door can be provided which may be lightened by providing lightening holes 182 in the ribs to serve also for shrinkage purposes.

It is to be understood that we do not wish to be limited by the exact embodiment of the device shown, which is merely by way of illustration and not limitation, as various and other forms of the device will of course be apparent to those skilled in the

art without departing from the spirit of the invention or the scope of the claims.

We claim:

1. In a mechanism of the character described, the combination of a cast drop door provided with stiffening ribs, hinges for attaching the door to a mounting, means for securing the movable hinge elements to the door, and recesses formed within said door for receiving these elements, so designed as to relieve the securing means from stress when the door is in the normally closed position. 70

2. In a mechanism of the character described, the combination of a drop door, provided on its lower surface with a series of cast ribs to insure rigidity and a track for engagement of door closing means, marginal flanges for further increasing stiffness and rigidity, recesses formed by re-entrant sections of these flanges and the aforementioned cast ribs, to receive the moving element of the hinges, and means for securing said moving hinge elements to the door. 85

3. In a mechanism of the character described, the combination of hinges comprising stationary pivot members and movable elements, a drop door provided with two or more elongated cast depressions, stiffening webs on said door, pairs of ribs positioned on the under surface of the door at said depressed sections to act as bearing surfaces for suitable door closing means, recesses formed by the main door structure for receiving and retaining the movable elements of said hinges and means for securing said movable elements to the door casting. 90

4. A drop door provided with elongated cast depressions, stiffening webs and marginal reentrant flanges, pairs of ribs positioned on the under surface of the door at said depressed sections as bearing surfaces for suitable door closing means, together with recesses formed by elements of the door structure for securing suitable hinges. 105

5. In a dump door, the combination of a main sheet, marginal flanges formed thereon, said main sheet having paneled portions disposed between a pair of flanges, said panels having portions for cooperative relation with door operating mechanism, said panels merging into said sheet adjacent one of said flanges by sloping portions whereby when said door is moved to discharge positions no pocketing of the load will result. 115

6. In a dump door, the combination of a main sheet, marginal flanges formed thereon, said main sheet having paneled portions disposed between a pair of flanges, said panels having portions for cooperative relation with door operating mechanism, said panels merging into said sheet adjacent one of said flanges by sloping portions whereby when said door is moved to discharge posi- 125

- tions no pocketing of the load will result, and hinge butts secured to said sheet by means disposed in multiple shear.
7. In a door construction, a rigid reinforced door having a door closing track projecting from one surface thereof, a hinge receiving recess formed in said door located at the extremity of and between the extended projection of said track.
10. 8. In a dump door, the combination of a main sheet presenting an upper plane surface to the inside of a car, said sheet having depending marginal flanges, members formed on one of said flanges and on said sheet and disposed to form hinge pockets, and hinge butts fastened in said pockets by means disposed in multiple shear.
15. 9. In a dump door, the combination of a main sheet presenting an upper plane surface to the inside of a car, said sheet having depending marginal flanges, members formed on one of said flanges and on said sheet and disposed to form hinge pockets, bosses formed on said sheet, and hinge butts fastened in said pockets by means through said bosses and pocket whereby said means is disposed in double shear.
20. 10. In a dump door, the combination of a main sheet presenting an upper plane surface to the inside of a car, said sheet having depending marginal flanges, members formed on one of said flanges and on said sheet and disposed to form hinge pockets, and hinge butts disposed substantially in the plane of one of said flanges and fastened in said pockets by means disposed in multiple shear.
25. 11. In a dump door, the combination of a main sheet, hinge butts secured thereto, hinge brackets continually pivoted to said hinge butts and provided with a butt engaging bearing for supporting said butt whereby substantially no load is carried by the pivot between said butt and bracket in certain position of said door.
30. 12. In a dump door, the combination of a main sheet, marginal flanges formed thereon, said main sheet having paneled portions disposed between a pair of flanges, said panels having portions for cooperative relation with door operating mechanism.
35. 13. In a dump door, the combination of a main sheet, marginal flanges formed thereon, said main sheet having paneled portions disposed between a pair of flanges, said panels having portions for cooperative relation with door operating mechanism, hinge butt pockets formed in said sheet in substantial alignment with said panels, and hinge butts fastened therein.
40. 14. In a dump door, the combination of a main sheet, marginal flanges formed thereon, said main sheet having paneled portions disposed between a pair of flanges, said panels having portions for cooperative relation with door operating mechanism.
45. 15. In a dump door, the combination of a load supporting plate, hinge butt pockets formed in said sheet in substantial alignment with said panels, and hinge butts fastened therein by means disposed in multiple shear.
50. 16. In a dump door, the combination of a load supporting plate, said plate being provided with spaced hinge butt securing portions, hinge butts disposed between said portions, and securing means passing through said portions and hinge butts for fastening said butts to said door.
55. 17. In a dump door, the combination of a load supporting plate, said plate being provided with spaced substantially parallel hinge butt securing portions, hinge butts disposed between said portions, and securing means passing through said portions and hinge butts for fastening said butts to said door.
60. 18. In a dump door, the combination of a load supporting plate, said plate being provided with a member spaced from said plate and forming a recess, a hinge butt disposed between said member and plate and in said recess, and securing means passing through said butt, said plate and said member for fastening said butt to said door.
65. 19. In a dump door, the combination of a load supporting plate, said plate being provided with a hinge butt securing portion, a hinge butt provided with means for securing said butt to said portion, said portion being thickened to receive said butt securing means, said butt being provided with a shoulder adapted to engage said plate for positioning said butt with respect to said plate.
70. 20. In a dump door, the combination of a load supporting plate, a hinge butt secured to said plate, said butt being provided with a shoulder adapted to have cooperative engagement with said plate for positioning said butt with respect to said plate.
75. 21. In a dump door, the combination of a load supporting plate, a hinge butt secured to said plate, a hinge member pivotally mounted to said hinge butt, said member being provided with means engaging a portion of said butt for at least partially supporting said butt in all operative positions of said door.
80. 22. In a dump door, the combination of a load supporting plate, a hinge butt secured to said plate, a hinge member pivotally mounted to said hinge butt, said member being provided with arcuate frictional sup-
85. 90. 95. 100. 105. 110. 115. 120. 125. 130.

porting means for at least partially supporting said hinge butt in all positions of operation of said door.

23. In a dump door, the combination of a load supporting plate, said plate being provided with spaced hinge butt securing portions, a hinge butt disposed between said portions, and securing means disposed substantially parallel to said plate and passing through said portions and said hinge butt for fastening said butt to said door.

24. In a dump door, the combination of a load supporting plate, said plate being provided with a track adapted to have controlling operation with operating means for controlling opening and closing of said door, said track being provided with spaced portions adjacent one edge of said plate forming with said plate a recess for the reception of a hinge butt, a hinge butt disposed in said recess, and securing means fastening said hinge butt to said door.

25. In a dump door, the combination of a load supporting plate, said plate being provided with a track adapted to have cooperation with operating means for controlling opening and closing of said door, said track being provided with spaced portions adjacent one edge of said plate forming with said plate a recess for the reception of a hinge butt, a hinge butt disposed in said recess, and fastening means cooperating with said hinge butt and said spaced portions for securing said hinge butt to said door.

26. In a dump door, the combination of a load supporting plate, said plate being provided with a track adapted to have cooperation with operating means for controlling opening and closing of said door, said track being provided with spaced portions adjacent one edge of said plate forming with said plate a recess for the reception of a hinge butt, a hinge butt disposed in said recess, and fastening means cooperating with said hinge butt and spaced track portions for securing said hinge butt to said door, said hinge butt being provided with means cooperating with said door for positioning said butt in said recess.

27. In a dump door, the combination of a load supporting plate having integral marginal flanges, said plate being provided with a track integral with a plurality of opposite flanges and adapted to have cooperation with operating means for controlling opening and closing of said door, said track being provided with spaced portions adjacent one edge of said plate and forming with said plate a recess for reception of a hinge butt, a hinge butt disposed in said recess and securing means fastening said hinge butt to said door.

28. In a dump door, the combination of a load supporting plate having integral mar-

ginal flanges, said plate being provided with a track integral with a plurality of opposite flanges and adapted to have cooperation with operating means for controlling opening and closing of said door, said track being provided with spaced portions adjacent one edge of said plate and forming with said plate a recess for reception of a hinge butt, a hinge butt disposed in said recess, and securing means cooperating with said hinge butt and said spaced portions for securing said hinge butt to said door.

29. In a dump door, the combination of a load supporting plate provided with a track adapted to have cooperation with operating means for controlling opening and closing of the door, said plate being provided with spaced panels and reinforcing means disposed between and connecting said panels.

30. In a dump door, the combination of a load supporting plate, said plate being provided with a track adapted to have cooperation with operating means for controlling opening and closing of said door, spaced panels formed in said plate, and reinforcing ribs formed integral with said plate and connecting said panels.

31. In a dump door, the combination of a load supporting plate having spaced depressed panels formed therein, said panels extending toward a free edge of said door, said panels being formed to dispose a sloped portion toward said free edge whereby material will tend to flow from said panels when said doors are in dumped position and reinforcing means merging into said panels.

32. In a dump door, the combination of a load supporting plate, said plate being provided with panels disposed therein, and hinge butt recesses formed in said plate substantially in alignment with said panels.

33. In a dump door, the combination of a load supporting plate having marginal flanges, said plate being provided with panels therein extending between but independent of at least one of said marginal flanges, hinge butt recesses formed in said plate substantially in alignment with said panels and intersecting a portion of one of said marginal flanges.

34. In a dump door, the combination of a load supporting plate having marginal flanges, said plate being provided with panels therein extending between but independent of at least one of said marginal flanges, hinge butt recesses formed in said plate substantially in alignment with said panels and intersecting a portion of one of said marginal flanges, said panels each being provided with a track adapted to have cooperation with operating means for controlling opening and closing of said door.

35. In a dump door, the combination of a load supporting plate having marginal flanges, said plate being provided with pan-

els therein extending between but independent of at least one of said marginal flanges, hinge butt recesses formed in said plate substantially in alignment with said panels and intersecting a portion of one of said marginal flanges, and means connecting said panels and integral with said plate.

36. In a dump door, the combination of a load supporting plate having marginal flanges, said plate being provided with panels therein extending between but independent of at least one of said marginal flanges, hinge butt recesses formed in said plate substantially in alignment with said panels and intersecting a portion of one of said marginal flanges, said panels each being provided with a track adapted to have cooperation with operating means for controlling opening and closing of said door, and means connecting said panels and integral with said plate.

Signed at Chicago, Illinois, this 20th day of April, 1929.
